UNITED STATES PATENT OFFICE.

ERNEST L. CASE, OF MINNEAPOLIS, MINNESOTA.

VALVE-LIFTER.

1,171,089.

Specification of Letters Patent.

Patented Feb. 8, 1916.

Application filed June 14, 1915. Serial No. 34,052.

To all whom it may concern:

Be it known that I, ERNEST L. CASE, citizen of the United States, resident of Minneapolis, county of Hennepin, State of Minnesota, have invented certain new and useful Improvements in Valve-Lifters, of which the following is a specification.

My invention relates to tools for handling the valves of a gas engine and the object 10 of the invention is to provide a device by means of which a valve can be easily and quickly removed from its seat and as readily replaced.

A further object is to provide a tool of 15 simple construction and one which will be very strong and durable.

The invention consists generally in various constructions and combinations, all as hereinafter described and particularly 20 pointed out in the claims.

In the accompanying drawings forming part of this specification, Figure 1 is a view, partially in section, through a valve and its seat, showing the tool in position for removing the valve, Fig. 2 is a sectional view 25 on the line $x-x$ of Fig. 1, Fig. 3 is an enlarged detail view of the jaws of the tool. Fig. 4 is a detail view, showing the tool adapted for removing the valve in another 30 way.

In the drawing, 2 represents a valve having a seat 3. It is often necessary to remove these valves from an engine for the purpose of grinding or cleaning them or for 35 repairs and it sometimes is difficult to effect this removal easily and conveniently. I therefore provide a tool having jaws 4 and 5 pivotally connected at 6 and provided with handles 7 and 8. These jaws are wedge-shaped in cross section, as indicated in Fig. 2, with their tapered edges arranged to lap by one another when the jaws are closed. The disk of the valve is provided with a slot 9 therein adapted to receive the ends 40 of the jaws and when the handles are pressed together thelapping edges of the jaws will slide upon one another and their outer faces 45

will be forced against the walls of the slot and clamped firmly thereon, and the harder the handles are squeezed together the greater 50 will be the outward pressure of the jaws on the walls of the slot, and when these jaws have been securely clamped, an upward pull on the tool will remove the valve from its seat.

In some cases the valve disk is provided with holes 10 therein and I therefore provide the ends of the handles with roughened faces 11 which are adapted to engage the walls of these holes when the tool is inverted, and by pressing these handles together sufficient friction may be produced between the roughened surfaces and the walls of the holes to enable the operator 60 to easily handle the valve.

The tool may be made in various sizes and in various ways; the details of construction herein shown and described may be modified and still be within the scope of my invention.

I claim as my invention:

1. A valve lifting tool having handles pivotally connected to one another and provided with jaws, wedge-shaped in cross section and adapted to lap by one another and having ends for entering a slot in the valve 75 disk, for the purpose specified.

2. A valve lifting tool having jaws provided with ends for entering a slot in the valve disk, said jaws lapping by one another and formed to exert when squeezed together 80 an outward pressure on the walls of the slot, substantially as described.

3. A valve lifting tool comprising handles having jaws for gripping opposing walls provided in the upper surface of a valve 85 disk.

4. A valve lifting tool having jaws adapted to enter a slot in a valve disk, said jaws being formed to exert when closed an outward pressure on the walls of the slot to 90 lock the tool therein.

In witness whereof, I have hereunto set my hand this 11th day of June 1915.

ERNEST L. CASE.
